STARTING BLOCK

Filed July 31, 1934

INVENTOR.

INVENTI
E.F. NIDAY

B. J. Craig,
ATTORNEY.

This invention relates to starting blocks for use by runners, and more particularly to a novel starting block which includes a frame and means to support a foot plate upon the frame.

UNITED STATES PATENT OFFICE

2,004,172

STARTING BLOCK

Everett F. Niday, Altadena, Calif.

Application July 31, 1934, Serial No. 737,733

8 Claims. (Cl. 272—59)

This invention relates to starting blocks.

The general object of the invention is to provide an improved starting block for the use of runners.

A more specific object of the invention is to provide a novel starting block which includes a frame and means to support a foot plate upon the frame.

A further object of the invention is to provide a starting block including a novel foot plate and brace which collapses flat when not in use.

Other objects and the advantages of my invention will be apparent from the following description taken in connection with the accompanying drawing wherein:

Fig. 1 is a central sectional view of a starting block embodying the features of my invention;

Fig. 2 is a top plan view of the block;

Fig. 3 is a fragmentary side elevation showing the foot plate in another position; and,

Fig. 4 is a fragmentary section taken on line 4—4 of Fig. 2 and showing two of the blocks secured together.

Referring to the drawing by reference characters I have indicated my starting block generally at 10. As shown the starting block is preferably made of metal and comprises a body indicated generally at 11, a foot plate indicated at 12, and a brace member indicated generally at 13.

The body 11 includes a pair of side members 14 which are held in parallel spaced apart relation by end members 15 and 16. The end member 16 is somewhat longer than the end member 15 and serves as a toe plate which the toe of the runner's shoe may engage.

At the junction of the sides and ends I provide downwardly projecting spike members 17 which are adapted to be pushed into the ground to hold the starting block against movement.

The spike members 17 are tapered and the body 11 has holes 18 corresponding in taper and position to that of the spikes 17 so that two of the blocks may be brought together with the bottoms adjacent and with the spikes 17 in the holes 18 where the taper holds the blocks together. To prevent the blocks from separating I may provide pockets 19 having shoulders 19' therein on each block which receive resilient tongues 21 having releasable locking members 22 thereon. When not in use the tongues 21 may be swung into the position shown in Fig. 2.

The foot plate comprises a member having a shaft 20 at its forward end which passes through apertures 21' in the side members 14. The foot

plate is provided with side flanges 22' and with an end portion 23, and the side flange is recessed to form pockets 24 and 25. The foot plate is provided with a boss 26 which is apertured as at 27 and through which one end of a spring 28 extends. The other end of the spring 28 is secured by a screw 29 to the lower surface of the toe plate 16. The spring 28 tends to normally urge the foot plate to a position between the side members 14.

The brace member 13 includes a pair of arms 30 which are held in spaced apart relation by a cross member 31 and the arms 30 are pivoted on a shaft 32 which passes through holes in the side members 14.

Each of the arms 30 is provided with a lug 33 and these lugs 33 are adapted to fit in either of the pockets 24 or 25 to vary the inclination of the foot plate. The brace member 13 in collapsed position fits between the side walls 14 and to prevent undue movement the end of one of the arms 30 (see Fig. 4) is notched as at 34 and in folded position of the arm the notch 34 engages the end of a spring 35 which is secured to the cross member 15 by a screw 36.

The end portion 23 of the foot plate is narrower than the body of the foot plate and fits between the arms 30 (as shown in Fig. 2) and engages inwardly directed lugs 37 on the arms 30 to thereby limit the downward movement of the foot plate.

The foot plate is shown as provided with a recess 38 in which an engaging member 39 which may be made of wood, rubber or other material may be positioned to form a better gripping surface for the runner.

The side members 14 are preferably provided with a scale of graduations 40 to aid the runner to accurately position the starting blocks.

In use the foot plate 12 is raised against the tension of the spring 28 and the brace member is moved so that the lugs 33 thereon fit one of the pockets 24 or 25. The spikes 17 are then inserted in the ground and the block is ready for use.

From the foregoing description it will be apparent that I have invented a novel starting block which is very simple in construction and which is highly efficient in use.

Having thus described my invention, I claim:

1. In a starting block, a body comprising a rectangular frame, a brace pivoted to said body between the sides of said frame, a foot plate pivotally mounted on said body between the sides 55

- of said frame and means to adjustably connect one end of the foot plate to the brace.
2. In a starting block, a body comprising a frame having sides and having means thereon adapted to be embedded in a running surface, a brace pivoted at one end to said body a foot plate pivoted at one end to said body, spring means to normally urge said foot plate between the sides of the frame, and means on the other end of the foot plate to engage the brace.
3. In a starting block, a body having means thereon adapted to engage the surface of a running track, said body including longitudinally extending spaced side members and end members, a foot plate, means to pivotally mount one end of said foot plate between said side members, a brace, said brace including one end portion fitted between said side members and fixedly pivoted to the side members, and means on the other end of the brace member releasably engaging the other end of the foot plate to hold the foot plate in elevated position.
4. In a starting block, a body means thereon adapted to engage the surface of a running race, said body including longitudinally extending spaced side members, a foot plate, means to fixedly pivot said foot plate between said side members, a brace, means to fixedly pivot said brace between said side members, a pair of grooves on the foot plate and means on the brace member releasably engaging the grooves of the foot plate to hold the foot plate in elevated position.
5. In a starting block, a rectangular frame having spaced sides and spaced ends, a brace pivotally mounted between said sides at one end of said frame, a foot plate, means to pivot said foot plate on said frame between said sides, said brace having means thereon engaging the foot plate, said foot plate including a body adapted to be en-
- gaged by the sole of the shoe of the user, said frame having tapered spikes on the bottom thereof to engage the surface of a running track, said frame having tapered holes therein adjacent the spikes and corresponding in taper to the taper of the spikes.
6. In a starting block, a rectangular body having parallel sides, said sides having opposed holes therein, a brace having a shaft at one end passing through said holes, a foot plate, said foot plate at one end having a shaft passing through said sides, said brace at the other end having means thereon engaging the foot plate, said foot plate including a body, said body having a recess, a bearing member in said recess adapted to be engaged by the sole of the shoe of the user.
7. In a starting block, a body having means thereon adapted to engage the surface of a running track, said body including longitudinally extending spaced side members and end members, a foot plate, a fixed shaft passing through said foot plate and said side members whereby the foot plate is pivoted, a brace, means passing through one end of said brace and said side members whereby the brace is pivoted to the side members, and means on the other end of the brace member releasably engaging the foot plate to hold the foot plate in elevated position.
8. In a starting block, a body having sides, a brace pivotally mounted at one end of said body, a foot plate on said body, said brace means thereon releasably engaging the foot plate, said foot plate including a part adapted to be engaged by the sole of the shoe of the user, said body having a shouldered pocket at one end and having a locking tongue at the other end adapted to engage within the shouldered pocket of a similar adjacent block.

EVERETT F. NIDAY.
